Fig. 1

FIG. 1 is a side elevational view of an invertible candlestick showing my new design with the candle shown in broken lines for illustrative purpose only;

FIG. 2 is a perspective view of a second embodiment of my new design on an enlarged scale, the second embodiment differing from the first only in the "cracked" surface pattern; and

FIGS. 3 and 4 are respectively top and bottom plan views common to both embodiments.

I claim:

The ornamental design for an invertible candlestick, substantially as shown and described.
